CLAIM

The ornamental design for a rake attachment, as shown and described.

DESCRIPTION

FIG. 1 is a perspective view of a rake attachment taken from above and from one side showing my new design, the opposite side being a mirror image of that shown;

FIG. 2 is a side view thereof;

FIG. 3 is a rear elevational view thereof;

FIG. 4 is a front elevational view thereof;

FIG. 5 is a top front perspective view thereof; and,

FIG. 6 is a bottom rear perspective view thereof.

FIG. 4

FIG. 3
